TOOL INDUCTION ELIMINATION APPARATUS
FOR ELECTRIC CONTROL CIRCUITSEdwin M. Callender, Cynwyd, Pa., assignor to The
Budd Company, Philadelphia, Pa., a corpora-
tion of Pennsylvania

Application December 6, 1947, Serial No. 790,192

13 Claims. (Cl. 219—4)

1

This invention relates to improved means for neutralizing the inductive effect of the parts of a tool, such as a welding tool, when utilized as part of the power supply circuit from a source of alternating current.

In my copending application, Serial No. 630,401, filed November 23, 1945, now Patent No. 2,472,043, dated May 31, 1949, there is shown and described an electrical control system which is dependent for functioning upon the change of load in a load circuit to which the control system is connected. The particular application of this circuit is to a resistance welder having electrodes and a tool yoke which in the operation of the apparatus develops an inductive voltage introducing an inaccuracy in the value of the control voltage. To overcome this inductive voltage, there is supplied in this circuit, an inductor subject to adjustment which by its action lessens or neutralizes the inductive effect of the tool and thus secures for the control system correct action.

In the present application, which is a continuation in part of the application above referred to, I employ the method and apparatus of said application and also modified and improved means for accomplishing the neutralization of tool inductive voltage.

The objects of this invention may be stated as follows: to provide effective means to neutralize inductive voltage in a signal circuit which develops from a tool connected to the signal circuit; to provide tool inductive voltage neutralizing means in which transformers are substantially eliminated; to provide neutralizing means for tool inductive voltages which may be set up either at the tool or at points removed from the tool; to provide a neutralizer for tool inductive voltages which is chiefly dependent upon voltage transmission as distinguished from power transmission; to provide a neutralizer of the mentioned type in which high excitation transmission is avoided; to provide a neutralizer in which the time lag in the operation of the control voltage is reduced to a negligible value; to provide a neutralizer which may be made a part of and subject to operation of the current compensation circuit; and to provide neutralization means which, when adjusted, is fixed for all ordinary variable conditions that may occur in the operation of the tool.

In order to set out the features of the invention with clarity, the neutralizing circuit for the tool inductive voltage is shown and described as applied to a resistance welding circuit although

2

it is apparent that the circuit has utility in other relationships.

Reference is made to the following description based on the figures of drawing including:

5 Figure 1 showing a resistance welding circuit provided with combined current compensation and tool voltage neutralization;

10 Figure 2 showing a modification in which a transformer type neutralizer of tool voltage is employed as distinguished from a fast resistance-tube neutralizer; and

15 Figure 3 showing a modification in which the neutralizer is structurally one with the tool itself.

Like parts bear similar numbers in the various views.

20 In the drawing, the circuit may be divided into various sections, lettered A, B, C, D, E, F and G, indicating, in general, different functions of the circuit. A indicates the usual power and timing controls. B denotes the power circuit of a welder including the tool structure and electrodes and power source. C indicates the neutralizing device for the tool inductive voltage. D denotes the current compensation circuit. E refers to the current rectifying and voltage amplifying circuit, F to the voltage control circuit, and G to the apparatus operated by the control circuit.

25 In greater detail in section B, there is indicated at 1, a load comprising two overlying metal plates adapted to be welded together. These plates are placed between the electrodes 2 and 3, the electrodes, in turn, having connection through yoke arms 4 and 5 to the tool standard 6. Power is supplied the electrodes 2 and 3 from the A. C. source 7 of the A circuit through the ignitrons 8 and 9 and welding transformer 10, including the primary coil 11, secondary coil 12 and secondary conductors 13.

30 Conventional control of the power supply is diagrammatically indicated in the A section by the boxed units 15 and 16, designating respectively the power control and the timing control. The power control, in conjunction with the phase shift 17, selects the fraction of the half cycle 35 of the supply current to be utilized at the weld and the timing control determines the number of cycles of power application for each weld. Details of these controls are more clearly shown in my copending application to which reference is made hereinabove.

40 The C, D, E and F circuit sections constitute the corrective, amplifying and control circuits which are effective for operating translating devices, such as a cutout switch in the G section, the control being subject to load change for

operation. In the case of a resistance welding circuit, the change of resistance and voltage at the weld point due to fusion is the initiating factor in bringing about operation of the control circuit. Circuit connections for the signal amplifying circuit E are made in electrodes 2 and 3 at points 20 and 21, the conductors 22 passing through the yoke arms 4 and 5, and standard 6, extending from the tool, preferably intertwined as shown at 23, to reduce inductance, to two resistors 24 and 25, connected in series in the tool circuit 21-23.

Resistor 25 is variable and is included in a shunt circuit from the current compensator circuit D, as will be more fully described herein-after. The terminals 26 and 27 of resistor 24 are connected through bias resistors to grids 28 and 29 respectively of triode vacuum tubes 30 and 31. The cathodes 32 and 33 of these tubes are connected together and to the midpoint of resistor 24 through a bias battery 34. The anodes 35 and 36 of the tubes 30 and 31 are connected together through two equal valued resistors 37 and 38 for which, in some uses, reactors may be used. A direct current source 39 is provided for the tube supply, connections being made at points 40 and 41 between the cathodes 32 and 33 and resistors 37 and 38 respectively. A smoothing capacitor 42 is also connected between points 40 and 41.

The tube system 30-31 is of the push-pull type and is provided primarily for amplification. Obviously, additional stages of tube amplification may be utilized as desired, as indicated at 43.

The amplified current from the tube system 30-31 is rectified and filtered by a full wave rectifier 44, resistor 44a and capacitors 44b and this rectified and smoothed current is led to resistor 45. A triode vacuum tube 46 and potentiometer resistor 47 are connected in parallel around the resistor 45, establishing output terminals 48 and 49 for the E branch circuit.

The tube 46 controls the voltage of the E section output points 48 and 49 on either side of the resistor 47. This control is obtained by variation of the effective resistance of the tube through change of bias of grid 46a within the tube. This bias varies so as to increase the resistance and thereby the voltage between points 48 and 49 when, due to an increase of current in the load circuit as brought about by weld fusion, for example, the signal voltage is less than its normal value.

The means for compensating for current change in the load circuit is specifically illustrated in the branch circuit D. A current transformer 50 is connected to the secondary of the load circuit, one side of the current transformer secondary being arranged with taps 51 and movable contact arm 51a to secure a variation in the value of the transformation. A conductor 52 leads from tap contact arm 51a through a reactor coil 53 to a potentiometer 54 where connection is made with the other conductor 55 of the current transformer. A variable shunt resistor 56 is connected across the transformer 50 to control the supply of power to the potentiometer, the resistance of resistor 56 being low compared with potentiometer 54 to insure proper control.

The output terminals 57 and 58 of the potentiometer 54 are connected to points 59 and 60 respectively, constituting inlet connections to a bridge rectifier 140. The outlet terminals 61 and 62 of this rectifier connect through conductors

63 and 64 respectively to a second potentiometer 65 to secure a desired direct current voltage for transmission to the control grid 75 of a pentode vacuum tube 70. Resistor 66 and capacitor 67 are employed for smoothing action on the rectified current flowing to the potentiometer 65. Leading from the inlet terminal 68 of potentiometer 65 a conductor 69 connects to the tube 70 at the cathode 71 and suppresser grid thereof. From outlet terminal 72, which is positive in relation to terminal 68, a conductor 73 leads through a constant potential in the form of a battery 74 and a resistor to the control grid 75 of the tube 70. There is thus impressed between the control grid 75 and the cathode 71 of tube 70, a voltage which is the sum of the constant voltage 74 and the rectified voltage due to the current in the load circuit and consequently, any change of current in the load circuit will be transmitted as a voltage change between points 72 and 68 to combine with the fixed voltage at the battery 74 and establish a variation in the bias of tube 70.

A voltage is applied across the anode 76 and cathode 71 of tube 70 from a source of constant direct current 77, there being employed a variable contact 47a on the resistor 47 to secure a desired value of applied voltage. The circuit from the source 77 passes from the positive side thereof through the resistor 47 to point 48 and thence through resistors 78 and 79 to the anode 76 of the tube. The negative terminal of the source 77 is connected by conductor 80 directly to the cathode 71 of the tube. Screen grid 81 is connected to point 82 intermediate the voltage point 48 and the resistor 78 and lying also in the connection between the cathode of tube 46 in the main signal circuit and point 48. The control grid 46a of tube 46, previously mentioned as controlling the voltage between points 48 and 49, is connected to the anode 76 of tube 70 through the resistor 79 and hence, the voltage of grid 46a is variable dependent upon the value of the current flowing through the tube 70 from source 77.

It thus appears that variation of the voltage between points 68 and 72 of the D circuit impresses on the control grid 75 of tube 70, a bias variation which, in turn, produces a variation in the grid bias of tube 46 and thereby produces between points 48 and 49, a voltage variation, the direction of which is such as to compensate for the change in current in the load circuit. Following this change more specifically and assuming polarity of the rectifier 140 and battery 74 of the D circuit as indicated, an increase in current in the load circuit, which would normally result from weld fusion, would bring about an increase in voltage between points 58 and 72, and this would add to the voltage of battery 74 to increase the negative bias of control grid 75 of tube 70. This would increase the effective resistance of tube 70 and increase the voltage between the anode and cathode of this tube, thereby making the grid 46a of tube 46 more positive and reducing the voltage between points 48 and 49 in the signal circuit. Accordingly, as regards current change, points 48 and 49 are compensated.

In describing the connections from the yoke of the welding tool through conductors 23 and resistors 24 and 25, description of the neutralizing circuit C, employed for overcoming the inductive effect of the tool yoke, was omitted for description at a later point. The neutralizing circuit comprises the reactor 53 in the conductor 52

of the D circuit, which reactor is provided with series of taps 53a and the movable contact 53b for transmission of modified reactance voltage to the variable resistor 25. The reactance is wound in such direction as to impress on resistor 25, a voltage opposite to that across resistor 24 due to voltage across the electrodes, i. e. 180° out of phase so that, since both resistors 24, 25 are in the signal circuit 22—23, a correction is imposed on the signal voltage to the extent of the opposing voltage across resistor 25. By appropriate adjustment of the reactance of coil 53 and the resistance of resistor 25 there may be obtained substantially exact neutralization of the inductive voltage of the tool in the signal circuit. This neutralization will be maintained so long as the surrounding conditions remain unchanged. Obviously, a new tool will require a new adjustment.

Hence, it now appears that the tool inductive voltage correction of the C circuit, coupled with the current change correction of the D circuit, permits establishment at output points 48 and 49 in the E circuit of a voltage value directly variable with the voltage across the electrodes.

The voltage control circuit F is connected directly to output points 48 and 49 of the E circuit. This circuit comprises a bridge normally unbalanced in one direction but which on balancing or unbalancing in the opposite direction, energizes mechanism of translating devices, such as relays, meters or motors. This bridge is formed of grid-controlled vacuum tubes 90 and 91 and resistors 92 and 93, each of these elements being connected in series with power inlet connections at junction points 94 and 95 (the latter being a potentiometer slider) and power outlet connections at junctions 96 and 97. The power inlet connections or junctions are supplied from an appropriate source of constant potential direct current as indicated at 98. Junction 95 is formed as a potentiometer slider in order to secure a variation of the balance of the bridge in preliminary settings, the bridge preferably being unbalanced for prevention of actuation of the translating devices prior to weld fusion.

The grid 90a of tube 90, forming one arm of the bridge, has connection through a resistor 99 to a point 100 intermediate resistors 101 and 102, connected across the outlet terminals 48 and 49 of the amplifying signal circuit and consequently, the negative bias on the grid of tube 90 will vary with the signal output of the points 48 and 49. The grid 91a of tube 91 in another of the arms of the bridge, has connection through resistors 103 and 104 to point 105 in conductor 106, connected to the negative terminal of source 98. In order to secure proportional values, the ratio of the resistances of resistor 104 to 103 is similar to that of resistor 102 to resistor 101. The grid 91a of this tube also has connection through the resistor 103, resistor 107 and capacitor 108 to conductor 106 at point 109. A rectifying circuit is provided to supply a charging current to the capacitor 108, including the rectifier 110, the cathode of which has connection to points 48 and 49 through a potentiometer 112, placed in parallel with resistors 101 and 102 across points 48 and 49. The potentiometer slide 113 permits variation in the percentage of the voltage drop between points 48 and 49 which is applicable to the grid 91a of bridge tube 91.

Points 96 and 97 of the bridge constitute the output points of the F section, as well as the bridge, and function to control current flow in a gas tube 114 in the G section through bias varia-

tion of the control grid 115 thereof, point 96 of the output having connection to the cathode 116 of this tube and point 97 having connection to the control grid 115. Power is supplied to this gas tube from a source 117 of constant potential direct current, the circuit including a variable resistor 118, a time delay relay coil 119 having a controlling resistor element 120, a relay coil 121 and a normally closed relay switch 122. Relay coil 121 when energized is adapted to open relay switch 111 included in the timing control circuit 112 of the B section.

The welding operation of the circuit is initiated by means of appropriate relay mechanism which may be indicated simply by a source of alternating current 123, having in series therewith a variable resistor 124, a manual switch 125 and a relay coil 126. The relay coil is adapted to close the relay switch 127 in the timing control circuit 112 of the A section so as to start the sequence of power supply and timing to bring about the welding cycle. This relay, also, when energized, closes relay switch 122 in the translating device circuit, including relay 121, and additionally 25 opens a normally closed relay switch 128 connected in shunt about the bridge capacitor 108. In the normally closed position of the switch 128, the capacitor is completely discharged but when opened, the charge on the capacitor is made effective on the grid of tube 91. The association of the relay switches 128, 122 and 127 to the relay coil 126 is indicated by broken lines.

The complete operation of the circuit may now be detailed. On closure of the manual initiating switch 125, relay switch 127 closes, instituting functioning of the timing and power control and starting a weld cycle at the electrodes. Closure of the initiating switch also opens relay switch 128, thus making effective on the grid of tube 40 91, the initial voltage of the control system comparable to that of the electrodes prior to weld fusion. Relay switch 122 also is closed.

Prior to weld fusion, the voltage at the electrodes is transmitted, amplified and rectified to 45 output points 48 and 49 with correction not only for current change if any, but also for tool yoke inductive voltage. From points 48 and 49, the initial voltage is transmitted to the F section bridge where a bias is established in the grids of tubes 90 and 91 while at the same time, a charge is formed on the capacitor 108 equivalent to the initial voltage value.

The slider 113 of potentiometer 112 is adjusted so that a bridge output is negative at terminal 55 96, giving a small negative bias on the control grid 115 of gas tube 114.

At weld fusion, the resistance at the weld and, consequently, the voltage changes, and this change is made at once effective at the grid of 60 tube 90. However, because of the capacitor 108 in the circuit of the grid of tube 91, the change of load voltage does not immediately take place in this tube and, therefore, the bridge is thrown out of balance in such direction as to develop 65 a positive potential at point 97 and the attached control grid 115 of tube 114, whereby this tube is caused to strike and power relay 121 is energized to open the cutout switch 111 in the timing control circuit 112. Thereupon the power circuit to the electrodes is opened.

It is apparent that the complete circuit, as described, involves control of a translating device or mechanism by voltage control means and that to secure accurate control, it is essential that 75 the voltage impressed on the voltage control

means reflect accurately the voltage change at the electrodes, brought about by weld fusion. The employment of current correction takes care of one phase of this problem. However, the effect of inductance of the yoke in a welding tool is so pronounced as to introduce substantial modification in the transmitted voltage so that unless correction be made for this inductive voltage, the operation of the translating device, such as the cutout, will be improperly timed and the entire control mechanism will operate incorrectly.

By using a neutralizing circuit as described employing resistances and electronic tubes, it is seen that the time lag of neutralization is practically eliminated. Since control circuits for electrical apparatus, such as welding tools, are usually complex, it becomes of considerable importance that time-consuming mechanism and circuits be eliminated as far as possible. This is apparent when it is understood that a welding cycle may be as short as 8 or 10 cycles of a 60-cycle current. The described resistance-tube arrangement for both tool inductive voltage neutralization and current compensation is a desirable solution of this problem.

Further, by combining the neutralizing and compensating circuits, they are made jointly subject to adjustment at tap switch 54a and compensation and neutralization thus constitutes a parallel operation which is continuously in step. The provision of the neutralizing resistor-reactor arrangement also avoids the necessity of placing a corrective inductive device directly on the tool itself as appears from a modification herein described and previously suggested in applicant's copending application above referred to, the control apparatus being installed in the timer assembly where it is not subject to accidental mal-adjustment or injury.

There are adaptations of control circuits of the type described, where conditions warrant the use of transformers because of the easy amplification and stable operating characteristics of this apparatus. In the modified circuit, as shown in Fig. 2, transformers are used of low ratio transformation so as to reduce the reactance and improve the time constant factor.

Referring to Fig. 2, there is disclosed the B-C-D-E sections of the complete circuit, as shown in Fig. 1, it being understood that these circuit sections may be substituted as a unit for the same lettered sections of Fig. 1.

The B section includes the tool with frame portions 4, 5 and 6 and electrodes 2 and 3. The signal conductors 22-23 are connected to the primary 159 of a transformer 151 and also to the secondary 152 of transformer 153. The primary 154 of transformer 153 forms part of a branch circuit, including reactor 53, having taps 53a and movable contact 53b to adjust for different values of reactance. The reactor forms a part also of the current compensation circuit, as will be more fully described hereinafter.

The secondary of transformer 151 establishes a potential across a resistor 155 and thereby impresses a control voltage on the control grid 156 of the tetrode vacuum tube 157. This tube forms part of an amplifying circuit, including a direct current voltage source 157a, bias resistor 158, capacitor 159, screen grid 160, anode 161 and primary 162 of a transformer 163.

The amplifying transformer 153 forms part also of a rectifier circuit for the signal current. There is included in this circuit, a full wave vacuum rectifier tube 164 with anodes 165 connected to

the terminals of secondary 166 of transformer 163, filter elements including the reactor 167 and capacitors 168, and the load resistance 45 having terminals 169 and 170. These terminals, in turn, connect respectively to E output terminals 48 and 49, terminals 170 and 49 being directly connected and terminals 169 and 48 being connected through the vacuum tube 46 as in Fig. 1. Output terminals 48 and 49 connect through points a and b to the control and apparatus circuits F and G, as in Fig. 1.

The operation of this modified neutralizer is similar to that of Fig. 1 in that the winding of the reactor 53 with the transformer 153 develops a voltage opposite to that of the signal voltage so that the inductive tool component of the signal voltage is neutralized.

The current compensator circuit D corresponds to the arrangement of Fig. 1 with the exception that instead of the potentiometer 54 being connected directly in parallel with the resistor 56, a transformer 117 is interposed between these elements. The D circuit otherwise is connected and functions as in Fig. 1.

In Fig. 3, there is shown the modification of the invention as disclosed in my copending application above referred to. In this arrangement, a reactor coil 120 is attached as by a support band 121 to the yoke 4-5-6 of the welder. This coil is placed in series in the signal circuit conductor 22 and hence, is subjected to the same inductive effects as the signal conductor. By placing the coil turns so as to develop voltage opposition to the signal voltage, the inductive effect is neutralized.

The signal conductors 22 are led from the tool directly to the step-up transformer 130 and thence to the rectifier unit 131, including full wave vacuum rectifier tube 132, reactor 133 and capacitors 134. Rectifier terminals 135, 136 are connected to the resistance load 45 and to the E output terminals 48 and 49 and thence to F connectors a and b in the manner previously described.

The current compensator circuit D is identical to that of Fig. 2 except that the reactor 53 and taps on current transformer secondary 50 are omitted.

The term "tool" is used in the specification and claims to denote any physical apparatus which by the shape thereof imparts inductive voltage to an attached or included electric circuit. Limitation of the word to welding equipment is not intended.

The specific neutralizing circuits disclosed, lend themselves especially to cooperative use with a voltage control system of the type shown in the drawing. However, adaptation to other uses may be made and limitation to the particular showing of the drawing is not intended, other than may be required by the claims as hereto appended.

What is claimed is:

1. Control apparatus comprising in combination, a source of alternating electric current, a current-consuming device connected to said source, control means including voltage comparator means conditioned by a pre-change voltage and susceptible to actuation by comparison of pre-change voltage with post-change voltage at said device due to change of electrical resistance in the work circuit thereof, said device normally inducing in said control means a voltage due to the passage of current in said work circuit, and neutralizing means connected to said

control means for neutralizing the inductive voltage due to the current flow in said work circuit, said neutralizing means comprising a resistor connected to said control means, and variable voltage means connected to said resistor adapted to impart a voltage therethrough counter to the induced voltage in said control means due to current flow in the work circuit.

2. Control apparatus comprising in combination, a source of alternating electric current, a current-consuming device connected to said source, control means including voltage comparator means conditioned by a pre-change voltage and susceptible to actuation by comparison of pre-change voltage with post-change voltage at said device due to change of electrical resistance in the work circuit thereof, said device normally inducing in said control means a voltage due to the passage of current in said work circuit, and neutralizing means connected to said control means for neutralizing the inductive voltage due to the current flow in said work circuit, said neutralizing means comprising a resistor connected to said control means, and an inductive reactor connected to both said load circuit and said resistor for imparting to the control means across said resistor a voltage variable with the induced voltage but 180° out of phase therewith, whereby the control voltage is corrected for the induced voltage.

3. Control apparatus comprising in combination, a source of alternating electric current, a current-consuming device connected to said source, control means including voltage comparator means conditioned by a pre-change voltage and susceptible to actuation by comparison of pre-change voltage with post-change voltage at said device due to change of electrical resistance in the work circuit thereof, said device normally inducing in said control means a voltage due to the passage of current in said work circuit, and neutralizing means connected to said control means for neutralizing the inductive voltage due to the current flow in said work circuit, said neutralizing means comprising a resistor connected to said control means, variable voltage means connected to said resistor adapted to impart a voltage therethrough counter to the induced voltage in said control means due to current flow in the work circuit, and means for maintaining a fixed ratio between the induced voltage and the neutralizing voltage.

4. In weld control apparatus, a source of alternating electric current, a welding tool yoke, electrodes attached to said yoke and adapted to receive electric current through said yoke from said current source for effecting welds, circuit connections between said source and electrodes through said yoke, control means susceptible to voltage change at the electrodes due to resistance change at weld fusion, circuit connections between said electrodes and control means, and neutralizing means connected to said electrode-control means connections for neutralizing the voltage at the electrodes due to the inductance of the tool yoke, said neutralizing means comprising an electrical transformation device connected to said electrode-control means connections and to said source-electrode connections for transmitting to said control means a voltage opposed and equal to the inductive voltage transmitted from the electrodes to the control means.

5. Control apparatus comprising in combination, a source of alternating electric current, a current-consuming device connected to said

source, control means including voltage comparator means conditioned by a pre-change voltage and susceptible to actuation by comparison of pre-change voltage with post-change voltage at said device due to change of electrical resistance in the work circuit thereof, said device normally inducing in said control means a voltage due to the passage of current in said work circuit, and neutralizing means connected to said control means for neutralizing the inductive voltage due to the current flow in said work circuit, said neutralizing means comprising a resistor connected to said control means, variable voltage means connected to said resistor adapted to impart a voltage therethrough counter to the induced voltage in said control means due to current flow in the work circuit, means for maintaining a fixed ratio between the induced voltage and the neutralizing voltage, and means for compensating in said voltage control means for voltage change therein due to current change in the load circuit.

6. In control apparatus, a source of alternating electric current, a current-consuming device electrically connected to said source, control means electrically connected to said device and operable by voltage change in the work circuit thereof, said device normally developing an induced voltage in said control means, a current transformer connected to the source-device circuit, and plural voltage transforming means connected from said transformer to said device-control circuit, one of said transforming means transmitting a voltage for neutralization of voltage in said device-control circuit due to induced voltage, and another of said transforming means compensating in said device-control source for current changes in said source-device circuit.

7. In control apparatus, a source of alternating electric current, a current-consuming device connected to said source, control means electrically connected to said device and operable by voltage change in the work circuit thereof, said device normally developing an induced voltage in said control means, and neutralizing means connected to said control means for neutralizing the induced voltage of said device in said control means, said neutralizing means comprising a transformer connected to said control means for impressing a voltage thereon counter to the induced voltage at the control means received from said device, and an inductive coupling between the device and transformer for transmitting current change due to inductive voltage at the device to said transformer.

8. In weld control apparatus, a source of alternating electric current, a welding tool yoke, electrodes attached to said yoke, circuit connections between said source and electrodes through sections of said yoke, control means including voltage comparator means conditioned by pre-fusion voltage and susceptible to actuation through comparison of pre-fusion voltage with post-fusion voltage at the electrodes, the change of voltage being due to change of resistance upon occurrence of fusion at welding, circuit connections between said electrodes and control means subject to inductive effects in said yoke, and neutralizing means connected to said electrode-control means connections for neutralizing the voltage formed at the electrodes due to the inductance of the tool yoke, said neutralizing means comprising a transformer electrically connected to the control means and electrodes, induction means between said voltage transformer and

said source-electrode circuit, and a variable reactor connected to the source-electrode connections and transformer whereby voltage approximately equal to and opposed to the inductive voltage of the tool yoke is transmitted to said control means.

9. In a weld control apparatus, a source of alternating electric current, a welding tool comprising a yoke and electrodes supported by said yoke, circuit connections between the source and electrodes passing through said yoke, switch means for establishing current supply to the electrodes at a substantially constant electrode voltage prior to fusion, control means including voltage comparator means conditioned by pre-fusion voltage and susceptible to actuation through comparison of pre-fusion voltage with post-fusion voltage connected to the switch means and electrodes and subject to inductive effects of current in said yoke and acting at the voltage change point due to weld fusion to actuate said switch means, a current transformer in said source-electrode circuit, a voltage transformer in said electrode-control means circuit, induction means between said voltage transformer and said source-electrode circuit, an inductive reactor electrically connected between said transformers, the winding relationship of the transformer-reactor-transformer system being such as to develop at the voltage transformer a voltage approximately equal and opposite to the induced voltage developed in the electrode-control means circuit by voltage change in the tool yoke, a rectifier connected to said current transformer, and electronic means operated by said rectified voltage for changing the control means voltage to compensate for current change in the source-electrode circuit.

10. In control apparatus in combination, a current-consuming device having a current supply circuit and a work circuit, a control circuit for measuring voltage change in a part of said work circuit and subject to an induced voltage due to current flowing in said work circuit which would objectionably influence the desired signal due to voltage change, a compensating circuit associated with said current supply circuit and producing an inductive effect in opposition to that induced in the control circuit by the work circuit, and means associating said compensating circuit and said control circuit in such manner as to impose the opposed inductive effect of the compensating circuit on the control circuit.

11. In control apparatus in combination, a current-consuming device having a current supply circuit and a work circuit, a control circuit for measuring voltage change in a part of said work circuit and subject to an induced voltage due to current flowing in said work circuit which would objectionably influence the desired signal due to voltage change, a compensating circuit associated with said current supply circuit and produc-

ing an inductive effect in opposition to that induced in the control circuit by the work circuit, and means associating said compensating circuit and said control circuit in such manner as to impose the opposed inductive effect of the compensating circuit on the control circuit, said associating means including a reactor coil in said compensating circuit, and circuit connections between said reactor coil and said control circuit.

10 12. In control apparatus in combination, a current-consuming device having a current supply circuit and a work circuit, a control circuit for measuring voltage change in a part of said work circuit and subject to an induced voltage due to

15 current flowing in said work circuit which would objectionably influence the desired signal due to voltage change, a compensating circuit associated with said current supply circuit and producing an inductive effect in opposition to that induced in the control circuit by the work circuit, and means associating said compensating circuit

20 and said control circuit in such manner as to impose the opposed inductive effect of the compensating circuit on the control circuit, said associating means including a reactor coil in said compensating circuit, and a shunt circuit connected with both said compensating circuit reactor coil and said control circuit.

13. In control apparatus in combination, a cur-

30 rent-consuming device having a current supply circuit and a work circuit, a control circuit for measuring voltage change in a part of said work circuit and subject to an induced voltage due to current flowing in said work circuit which would

35 objectionably influence the desired signal due to voltage change, a compensating circuit associated with said current supply circuit and producing an inductive effect in opposition to that induced in the control circuit by the work circuit,

40 and means associating said compensating circuit and said control circuit in such manner as to impose the opposed inductive effect of the compensating circuit on the control circuit, said associating means including a reactor coil in said compensating circuit, and a shunt circuit connected with said reactor coil and having an inductive connection as by a transformer with said control circuit.

EDWIN M. CALLENDER.
